TRIPLE DRESSER

Roland P. Carter, Lynchburg, Va., assignor to The Lane
Company, Inc., Altavista, Va.

Filed July 17, 1973, Ser. No. 379,942

Term of patent 14 years

Int. Cl. D6—04

U.S. Cl. D6—164

Fig. 1.

FIG. 2.

FIG. 1 is a side perspective view of a triple dresser showing my design; and

FIG. 2 is a front perspective view thereof.

The side of the dresser not shown is a mirror image of the side shown while the back is plain and unornamented.

I claim:

The ornamental design for a triple dresser, as shown and described.
